STORAGE TANK

James M. Chittim, San Antonio, Tex.

Application September 2, 1937, Serial No. 162,127

5 Claims. (Cl. 62—1)

This invention relates to new and useful improvements in storage tanks and in particular to the dispensing and regulating means connected with said tanks.

5 In localities where natural gas is not available from pipe lines, it is sometimes the practice to use a private storage tank, usually located underground, wherein liquefied butane, propane, or a mixture of similar gases may be stored. A 10 service line leads from the tank to the point of use, thus providing a gas supply similar to that provided by the aforementioned natural gas pipe lines. For safety, these tanks are constructed with a number of valves and pipes which require attention to insure their proper operation.

15 It is one of the objects of this invention to provide improved dispensing means mounted on such a tank as described, wherein all the necessary valves and pipes are mounted on a single 20 plate or head, so designed that the whole assembly may be removed as a unit, to be serviced or replaced.

25 Another object of the invention is to provide improved dispensing means for a storage tank wherein a suitable housing is provided for the dispensing means, said housing being easily removable without entailing any excavation.

30 A further object of the invention is to provide improved dispensing means for a storage tank wherein allowance is made for the surrounding earth to shift or settle without causing a fracture of, or putting an excess strain on, the supply pipe, and thereby occasioning a fire hazard by allowing the gas to escape.

35 A still further object of this invention is to provide improved dispensing means for a storage tank wherein the various valves are mounted directly in a head instead of on pipes which would be liable to breaking and cracking, thus setting up a hazardous condition.

40 Another object of this invention is to provide improved dispensing means for a storage tank, having an inlet valve and a vapor valve, whereby a hose leading from the bottom of a portable fuel supply which is utilized to fill the underground tank, may be connected to the inlet valve, and another hose connected from the vapor valve to the top of said supply tank, thus setting up a vapor balance between the two tanks, which 45 enables a gravity feed to be used in filling the storage tank and still allows no gas or vapor to escape to the open air.

45 A construction designed to carry out the invention will be hereinafter described, together with other features of the invention.

The invention will be more readily understood from a reading of the following specification and by reference to the accompanying drawings, in which an example of the invention is shown and wherein:

Figure 1 is a side elevation of the device mounted on a storage tank,

Figure 2 is an end view of the same with the housing broken away to show the interior construction,

Figure 3 is an enlarged sectional view taken on the line 3—3 of Figure 2,

Figure 4 is a sectional view taken on the line 4—4 of Figure 2,

Figure 5 is an enlarged sectional view taken on the line 5—5 of Figure 2, and

Figure 6 is an enlarged sectional view taken on the line 6—6 of Figure 4.

In the drawings the numeral 10 designates an elongated cylindrical storage tank of the usual type used for underground storage of liquids. It is designed so as to rest on angular supports 11, and has a circular opening in its upper surface 12' wherein a flanged collar 12 is welded or otherwise suitably mounted. A cap plate 13, which carries elements to be described later, is secured to the flanged collar by bolts 14. Supporting bars 15 extend radially from the flange of the collar and have their inner ends secured thereto by the bolts 14. The lower end of a cylindrical housing 16 surrounds the flange 12' of the collar 12 and the cap plate 13, and has its upper end projecting slightly above the ground level when the tank is suitably situated in the ground. The housing has angular retaining members 17 welded to its lower inner surface, which members are located to rest upon the bars 15, to which they may be fastened by bolts 18, whereby the housing 16 is suitably supported. As will be seen in the drawings, the housing has vertical walls and is of sufficient diameter as to allow the ready removal of the cap plate 13 and its supported elements. Also by removing the bolts 18 the housing itself may be removed if so desired. A cover 19 is secured to the housing by a hinge 20 and fastened by a hasp 21, allowing it to be locked, whereby tampering may be guarded against. The cover prevents foreign matter and excess water from entering the housing and injuring the contents thereof. As is shown in Figure 5, the housing has an open bottom 22, whereby any water entering said housing may flow out.

Also, notches 16' are provided in the wall of the housing at the upper end thereof and permit

vapors which may accumulate within the housing to escape therefrom.

The dispensing and regulating apparatus proper consists of a plurality of inlet and check valves, 5 all mounted in the cap plate 13. This allows them to be serviced as a unit, and to be easily removed and replaced if desired. The whole unit consisting of the cap plate and valves may be removed and replaced with a similar unit. In this 10 manner the gas supply is not cut off for any appreciable length of time.

The valves may be mounted in any convenient fashion but it is preferable to mount them as shown in the drawings. An inlet or filler valve 15 30 is mounted on the cap plate, being threaded into a screw-threaded opening 31 in said plate. A back flow check valve 32 is threaded into the bottom portion of the opening 31. The inlet valve is so constructed that when the hose from 20 the supply truck (not shown) is placed thereon it will open the valve. Should the truck move during the filling operation, and break the hose, the back flow check valve 32 would automatically close when the gas started escaping and prevent 25 any further loss. When the tank is not being filled these two valves are inactive and serve as a double seal against leakage. A slip tube gauge 33 is mounted in the plate 13 and has its tube 34 30 extending down in the tank. When these storage tanks are refilled, the filling is done by a gravity feed. Usually in cold weather there is a pressure 35 differential between the service or supply tank and the storage tank which is mounted in the ground. For equalizing the pressure in the two tanks a vapor valve 35 is provided in the cap plate 13. A hose is connected from the bottom of the supply tank to the inlet valve, thereby opening the latter, and another hose is connected from the 40 vapor valve to the top of the supply tank. Any pressure difference adjusts itself through the second hose, thus allowing the liquid to flow from the truck by gravity to the storage tank underground. An excess flow check valve 38 is mounted 45 in the same opening as the vapor valve 35, and extends into the tank. Should the second hose which is connected to the valve 35 break, any loss or escape of vapor would be prevented. It is pointed out that both the vapor valve 35 50 and inlet valve 30 are manually operated and that both are normally in a closed position. A safety relief valve 36 is also provided to take care of any sudden increases in pressure which would exceed the safe operating pressure of the storage tank.

A supply line 38 leads from the cap plate 13 to conduct the gas to its point of use. A valve 40 similar to the valve 38 is mounted on the inlet end of this line whereby, should the supply line break, 60 the valve 40 would automatically cut off the vapor passing to the line and thus prevent the loss of gas. A manual shut-off valve 41 is located in the supply line to allow the supply of gas to be shut off completely. A regulator 42 of the diaphragm type is mounted in the supply line between the shut-off valve and the point of use and 65 this regulator serves to keep the pressure constant at any predetermined range. If the pressure exceeds the range chosen as safe for operating conditions, a low-pressure valve (not shown) mounted within the diaphragm housing vents any 70 excess pressure through an opening 42' until the excessive pressure has subsided. The supply line leaving the regulator and passing through the 75 side wall of the housing is of copper tubing and

has a single loop or spiral therein. The tubing being of copper, and having the loop, is of sufficient flexibility to allow considerable shifting and settling of the tank and housing without a fracture occurring. Also a disturbance such as 5 an earthquake or nearby explosion would not crack the supply line and allow gas to escape. The copper line is connected to the regulator by a coupling 43. By disconnecting this coupling and the bolts 14 the cap plate and valves are 10 easily removed.

Each of these valves is obtainable on the open market and is subject to variation. Each valve serves an individual and specific purpose as set out hereinbefore. When the tank and housing is 15 suitably buried in the ground it is desirable to place a mixture A of pea-gravel and sand at the bottom of the housing, as is shown in Figure 1, thereby preventing dirt from washing into the housing and insuring the proper drainage of water 20 therefrom.

What I claim and desire to secure by Letters Patent is:

1. A storage and dispensing system for liquified gases, including, a storage tank having an 25 opening therein, a cover plate mounted in said opening, an inlet valve mounted in the cover plate, a back flow check valve mounted on the cover plate below the inlet valve so that the two valves communicate, a vapor valve mounted on 30 the cover plate, an excess flow check valve mounted on the cover plate below the vapor valve so that the two communicate, a safety valve mounted on said plate, a gauge mounted on said cover plate whereby the liquid level in the tank 35 may be ascertained, a supply line leading from the cover plate, a pressure regulator mounted in the supply line, and an excess flow check valve mounted in the cover plate below the supply line so that the line and valve communicate. 40

2. A storage and dispensing system for liquified gases including, a storage tank having an opening therein, a cover plate mounted in said opening, an inlet valve mounted in the cover plate, a back flow check valve mounted on the cover plate below the inlet valve so that the two valves communicate, a vapor valve mounted on 45 the cover plate, an excess flow check valve mounted on the cover plate below the vapor valve so that the two communicate, a safety valve mounted on said plate, a supply line leading from the cover plate, a pressure regulator mounted in the supply line, and an excess flow check valve mounted in the cover plate below the supply line so that the line and valve communicate. 50

3. A storage and dispensing system for liquified gases including a storage tank, a removable housing on said tank, a cover for said housing, a service line extending into said housing, a support for the service line in said housing, controls in said housing also carried by said support and removable as a unit therewith, said housing having its lower portion provided with drainage means to allow water to pass therefrom, said housing having its upper portion beneath said 60 cover provided with gas discharge means. 65

4. A storage dispensing system for liquified gas including a storage tank, an upstanding collar on said tank, a support on said collar, a housing for said support of larger diameter than said 70 collar, a service line extending into said housing and carried by said support, controls also carried by said support, said service line and controls being removable as a unit with said support, said housing being provided with drainage 75

means to permit egress of water from its lower portion and having its upper portion beneath said cover provided with gas discharge means.

5. A storage and dispensing system for liquefied gas including a storage tank, an upwardly disposed portion extending from said tank, a plate closing said upwardly disposed portion, a service line extending above said plate, controls for admitting and releasing the contents of the

10 tank, said service line and controls being sup-

ported at least in part by said plate, a housing forming an enlarged extension of said upwardly disposed portion, said housing being supported at least in part by said upwardly disposed portion, a cover for said housing, said housing being provided with drainage means to prevent escape of water from its lower portion and additional means for permitting escape of gas from its upper portion below said cover plate.
